[57] CLAIM

The ornamental design for a case for jewels, as shown and described.

DESCRIPTION

FIG. 1 is a perspective view of a case for jewels showing my new design with the lid in an open position; FIG. 2 is a front elevational view with the lid in a raised position;

FIG. 3 is a rear elevational view with the lid closing the case;

FIG. 4 is a cross-sectional view taken along line 4—4 of FIG. 3;

FIG. 5 is a right side elevational view of FIG. 3;

FIG. 6 is a left side elevational view of FIG. 3;

FIG. 7 is a top plan view of FIG. 3; and

FIG. 8 is a bottom plan view of FIG. 3.
